UNITED STATES PATENT OFFICE.

JULIUS KINDERVATER, OF NEW YORK, N. Y.

CONNECTING ROD FOR ENGINES.

Application filed April 5, 1923. Serial No. 630,048.

To all whom it may concern:

Be it known that I, JULIUS KINDERVATER, a citizen of the United States, residing at New York, in the county of New York and State of New York, have invented a new and useful Improvement in Connecting Rods for Engines, of which improvement the following is a specification.

This invention relates to the main connecting rods of locomotive engines, and particularly to the crank pin bearings thereof.

One object of the invention is to provide an improved construction of bearing, whereby the bearing brasses may be furnished with full flanges extending entirely around their peripheries, which flanges may be of adequate depth or extent of projection to hold said brasses securely from lateral displacement; and whereby such full-flanged brasses may be readily and conveniently applied within, or removed from, their receiving opening in the connecting rod head, without the necessity of resorting to the usual practice of increasing the depth of the inner end of the receiving opening for such purpose.

Another object of the invention is to provide a novel and improved construction of means for holding the brasses against longitudinal displacement, adjusting the brasses for taking up wear, and permitting the use of reconditioned brasses of reduced overall size.

Still another object of the invention is to provide a construction of the brasses, whereby removed worn brasses may be readily and conveniently salvaged or reconditioned for reapplication and continued service.

Still another object of the invention is to provide a method of quickly, conveniently and economically salvaging the brasses.

In the accompanying drawings, illustrating an embodiment of the invention,—

Figure 1 is a side view, in elevation, of the crank pin end of a connecting rod, showing the application of my invention thereto.

Figure 2 is a horizontal longitudinal central section through the same.

Figure 3 is a view, in elevation, showing the manner of applying or removing the outer end bearing brass.

Figure 4 is a similar view, showing the outer end bearing brass fitted in position, and illustrating the manner of applying or removing the inner end bearing brass.

Figure 5 is a perspective view of one of the bearing brasses per se.

Figures 6, 7 and 8 are views illustrating steps of the method of salvaging worn bearing brasses.

Referring now more particularly to the drawings, 1 designates the body of a locomotive engine main connecting rod, having, at its rear end, the crank pin bearing head 2, said head being provided with the usual opening 3 to receive the elements of the crank pin bearing. This opening is, as usual, of generally rectangular form, and, in accordance with my invention, is of the same depth throughout, i. e., the full distance between its vertical inner and outer end walls 4 and 5.

The crank pin bearing referred to, comprises two similar or counterpart half-bearing brasses 6 and 7, the body portions of which are of semi-annular form, the line of division between them being transverse to the axis of the rod. There is formed on each half-brass, a concave, semi-circular inner bearing face 8, and a convex, semi-circular outer peripheral surface or abutment face 9, said faces 8 and 9 being truly concentric, as shown in Fig. 5. The faces, 8 and 9, extend the full distance around the respective inner and outer surfaces of the semi-annular half-brass bodies, and intersect the inner and outer edges of end abutment faces 10. The end abutment faces 10, extend transversely on the half-bearing brasses, and are flat and parallel with each other, and with the ends of the opening in the head, the said faces 10, of the two half-brasses, abutting, when said half-brasses are properly assembled in the opening 3, to form a full closed bearing for and about the crank pin. Each half-brass is provided with full flanges 11, i. e., flanges extending around its ends, which flanges fit against the sides of the head 2, and thereby prevent lateral movement of the brasses. These flanges are of sufficient depth or extent of projection to ensure their firm and secure seating against the sides of the head, and the retention of the brasses against any undue lateral motion at all times.

The opening 3, may be made of somewhat greater length than usual, or the parts suitably proportioned to provide for the reception of filler blocks or liners, 12 and 13, which may be of counterpart form and con-

105
110

struction, and interchangeable in position. Each of the filler blocks or liners has a concave inner face 14, a flat outer face 15, parallel with one of the end walls, 4 and 5, of the opening 3, and flat top and bottom faces 16, parallel with the top and bottom walls, 4^a and 4^b, of said opening. The filler blocks 12 and 13, are of a width to fit snugly between the flanges 11, of the half-brasses, and 10 their concave faces 14, are curved to fit the convex surfaces 9 of the respective half-brasses, 6 and 7, against which they lie, the top and bottom faces 16, of the blocks, being adapted to squarely abut against the similar walls of the opening 3.

As shown, the block 12, is disposed between the bearing brass 6, and the outer end wall 5, of the opening 3, and its face 15, abuts directly against the wall 5, or against 20 a shim or thin auxiliary liner plate 17, fitted between said face 15, and the wall 5, while the block 13, is disposed between the bearing brass 7, and a follower wedge 18, and has its face 15, abutting against the vertical face 25 of said wedge 18. The wedge 18, is provided for cooperation with an adjusting wedge 19, for holding the bearing elements assembled, and for adjusting the same to take up wear on the bearing brasses. The 30 wedge 18, preferably extends the full depth of the opening 3, and its inclined face is of less length than the depth of the opening 3, and bears against the end wall 4, and has a threaded engagement with a bolt 20, whereby 35 it may be adjusted. The opposed faces of the parts, 13 and 18, may be provided, one with a groove 13^a and the other with a rib 18^a, or its equivalent, for interlocking engagement to hold said parts from lateral 40 displacement. For the purpose of securing accurate registration of the brasses and co-operating parts, and added security of retention of the parts in working position, I 45 preferably provide each filler block with a locking key for engagement with adjacent parts of the bearing. The block 12, for example, carries a key 21, threaded centrally in an opening therein, the ends of which key project beyond the faces, 14 and 15, in the 50 form of dowel pins or studs 22, which are adapted to freely engage seat recesses or openings 23 in the end wall 5 and body of the bearing brass 6. The block 13, carries a similar key 21, whose dowel portions 22, 55 freely engage seat recesses or openings 23, in the bearing brass 7 and wedge 18. These keys allow easy separation of the parts, when otherwise free for separation, and facilitate their accurate assemblage, while assisting in holding the parts firmly against 60 independent play or movement when in assembled relation.

An important feature of my invention resides in the ease and convenience with which 65 the full-flanged bearing brasses may be ap-

plied to, and removed from, the head 2. As shown in Figure 3, the bearing brass 6 may be applied, after block 12 has been fitted in position, by disposing it longitudinally in the opening 3, as indicated in dotted lines, 70 and then swinging or turning it half way around, as indicated in full lines, until it occupies its proper position. The bearing brass 7, may then, as shown in Figure 4, be applied, after block 13, has been fitted in position, by disposing it longitudinally in the opening 3 between parts 6 and 12, as indicated in dotted lines, and then swinging or turning it half way around, as indicated in full lines, until it occupies its proper position. The parts 7 and 13, may then be 75 slidably moved toward part 6, to close the bearing brasses about the crank pin inserted between them, and the wedges then applied and adjusted as required. By reversing 80 these operations, the bearing parts may be removed from the head 2, in an obvious manner. It will be observed that the construction described, allows proper clearance 85 to permit of such assemblage and separation of the bearing parts, without the necessity of resorting to a deepening of the opening 3 at one end, as heretofore required 90 for the purpose. An important advantage is thereby gained, in that the respective walls 95 of the opening 3, may be made continuous and as plane surfaces, allowing machining with greater ease and convenience, and with less time and labor. The omission of the 100 deepened portion of the opening also enables the use of interchangeable fillers at each end, which are essential elements in enabling 105 worn brasses to be rehabilitated and repeatedly used, in accordance with a method of rehabilitating the brasses to which my construction especially lends itself, as I will now proceed to describe.

Figure 6 shows a pair of bearing brasses 6 and 7, removed from the bearing head and relatively disposed as in use. In this view, the bearing faces 8 appear in full lines in original condition, the dotted lines 8^a, indicating the line of reduction of such surfaces from wear. In accordance with my method of salvaging these brasses, the 110 brasses, separately or conjointly, are subjected to bearing pressure, applied to their top and bottom surfaces, as to the ends of the surface 9, in the region of the abutment faces 10, such pressure serving to force such 115 top and bottom portions of the brasses inwardly or towards each other. As a result of this treatment each brass as a whole will be bent so that its abutment faces 10 diverge 120 or lie at angles to their normal plane, and its faces 8 will be varied from a semi-circular to a semi-elliptical form, as shown in 125 Figure 7. The faces 10, of each block, are then planed or otherwise trimmed off, as indicated by the dotted lines 10^a, in Figure 7, 130

so that said faces will again be brought to lie in parallel planes. The result of these steps is to reduce the arcs of curvature of the surfaces 8 and 9, so that the bearing 5 opening formed by the surfaces 8, and the periphery of the bearing formed by the surfaces 9, will be of less than normal diameters, i. e., the gaged diameter of these surfaces as in a new bearing. The planed faces 10^a, are 10 then sweated together, or otherwise united, to couple the pair of bearing brasses as a unit, in which condition they may be conveniently handled for the next two steps of treatment, shown in Figure 8, in which the 15 elliptical surfaces 8 are first bored from the elliptical contour 8^a, indicated in full lines, to a true circular contour, indicated by the dotted lines 8^b, of crank pin size (bearing diameter), and the surface 9, is then turned 20 from the full line elliptical contour 9^a, to the dotted line circular contour 9^b, concentric with the new circular bearing surface 8^b, formed as above described. The temporarily united surfaces 10^a are then separated 25 so as to release the half-brasses from each other, whereupon the brasses are ready for return to use. Worn bearing brasses thus renovated, are, on each renovating operation, slightly reduced in over all external dimensions, 30 from original or previous size, but this may be compensated for, in the direction of length of the bearing opening 3, by adjustment of the wedges and the use of interchangeable fillers, 12 and 13, of different 35 sizes or by the use of liners, reductions in the size of the brasses in the vertical direction, i. e., line of depth of the opening 3, being immaterial on account of the depth of the top and bottom portion of the full- 40 flanges 11, which, notwithstanding such successive reductions, always maintain an effective bearing depth. Bearing brasses thus constructed and mounted, may be repeatedly renovated for use, until reduced to a certain 45 degree, allowing long and continued use before the brasses are scrapped, with resultant economy.

It will be observed from the foregoing description, that my invention provides a 50 crank pin bearing which allows the use of full-flanged bearing brasses and, their application and removal without the necessity of deepening one end of the crank pin brass opening in the head for such purpose. Also 55 it will be seen that as the filler blocks embrace the brasses and fit between the flanges thereof, the use of holding flanges in the filler blocks is avoided, the flanges of the bearing brasses serving to hold both the 60 brasses and the filler blocks from lateral movement. As the filler blocks are locked in position by their keys, and interlock with the brasses, the brasses and blocks mutually 65 coact to brace and sustain each other, forming a strong and durable working connec-

tion, ensuring accurate registry of the parts and relief of any certain part from undue working strains. The form and construction of the half-brasses, as described, and the mode of mounting them employed, also 70 allows the brasses to be reconditioned from time to time as required, and the use of interchangeable fillers or liners adapts reconditioned brasses of various stages of reduction to be used in a ready, convenient 75 and efficient manner.

Having thus fully described my invention, I claim:

1. In a connecting rod bearing, the combination with a connecting rod having an opening in its head, of a pair of counterpart crank pin half-brasses, fitted in said opening, each of said brasses having end abutment surfaces, parallel with the ends of the opening, a concave semi-circular inner bearing surface, a convex semi-circular peripheral surface, said convex surface extending laterally from side to side of the brass on a continuous arc of curvature between and intersecting said end abutment surfaces truly 90 concentric with said concave inner bearing surface, and flanges integral with and extending around said peripheral surface at opposite sides thereof; and means, located in the opening of the head, for holding and 95 adjusting the brasses.

2. In a connecting rod bearing, the combination of a connecting rod, having a rectangular opening in its head, of equal depth from end to end thereof; a pair of half-brasses, fitted in said opening, each having a concave semi-circular inner bearing face, a convex periphery, and side flanges extending from said periphery; filler blocks having concave surfaces engaging the peripheral surfaces of the brasses, and lying between the side flanges of the respective brasses; and means located in the opening of the head, for confining and relatively adjusting said half-brasses and filler blocks. 105

3. In a connecting rod bearing, the combination of a connecting rod having a rectangular opening in its head, of equal depth from end to end thereof; a pair of counterpart half-brasses, fitted in said opening, each having a concave inner bearing face, a convex periphery, concentric with said bearing face, and side flanges extending from said periphery; filler blocks, fitted in the opening beyond the respective bearing brasses, each having a concave inner face and a flat outer face parallel with the ends of the opening, said concave faces of the blocks being adapted to bear against the peripheries of the brasses, and fitting between the side flanges thereof, the straight face of one of the blocks abutting on one end wall of the opening; and means, disposed between the other end wall of the opening and the other filler block, for confining and relating 115 120 125 130

tively adjusting said half-brasses and filler blocks.

4. In a connecting rod bearing, the combination of a connecting rod having an opening in its head, of oblong rectangular form and of equal depth throughout, the surfaces of the upper and lower walls of said opening being parallel and continuously plane; a pair of counterpart half-brasses fitted in said opening, each having a semi-circular inner bearing surface, a convex peripheral surface, and side flanges extending from said convex surface; filler blocks disposed in the opening beyond the brasses and having concave inner surfaces, lying between the side flanges, and engaging the convex surfaces of the adjacent brasses, each having plane upper and lower edges, engaging the plane top and bottom walls of the opening, and a straight vertical outer end edge; and means, located in the opening of the head, for confining and relatively adjusting said half-brasses and filler blocks.

5. In a connecting rod bearing, the combination of a connecting rod having an opening in its head; flanged half-brasses in said opening; filler blocks, lying outside said brasses and in contact with the outer surfaces of the same and between the flanges thereof, one of said filler blocks being disposed between one of the half-brasses and outer end wall of the opening; a detachable interlocking connection between said half-brass, filler block, and wall of the opening;

a follower wedge, in the opening, lying in contact with the outer side of the other filler block; a detachable interlocking connection between said filler block, the other half-brass, and said follower wedge; and an adjusting wedge, between said follower wedge and the other end wall of the opening.

6. In a connecting rod bearing, the combination of a connecting rod having an opening in its head, the outer end wall of said opening having a dowel seat; counterpart flanged half-brasses in said opening, provided with dowel seats; filler blocks on the outer sides of said brasses, engaging the outer faces of the same and lying between the side walls thereof, one of said filler blocks lying between the outer half-brass and outer end wall of the opening; a locking key, carried by said filler block and having dowel projections engaging the dowel seats in the outer half-brass and outer wall of the opening; a follower wedge, disposed in the opening, in contact with the outer side of the other filler block, and having a dowel seat therein; a locking key, carried by said filler block and having dowel portions engaging the dowel seats in the inner half-brass and follower wedge; and an adjusting wedge, between the follower wedge and inner wall of the opening and bearing on said follower wedge.

In testimony whereof I affix my signature.
JULIUS KINDERVATER.
